(57) CLAIM

I claim the ornamental design of a distributor for television signal, as shown and described.

DESCRIPTION

FIG. 1 is a top plan view of a distributor for television signal of my new design;

FIG. 2 is a front, elevational view of the distributor for television signal of FIG. 1;

FIG. 3 is a right side, elevational view of the distributor for television signal of FIG. 1;

FIG. 4 is a bottom plan view of the distributor for television signal of FIG. 1;

FIG. 5 is a left side, elevational view of the distributor for television signal of FIG. 1;

FIG. 6 is back, elevational view of the distributor for television signal of FIG. 1; and,

FIG. 7 is a front, perspective view of the distributor for television signal of FIG. 1.
